UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

WORK-GUIDING DEVICE FOR SEWING-MACHINES.

1,263,869.

Specification of Letters Patent. Patented Apr. 23, 1918.

Application filed April 1, 1916. Serial No. 88,205.

To all whom it may concern:

Be it known that I, ALBERT H. DE VOE, a citizen of the United States, residing at Westfield, in the county of Union and State 5 of New Jersey, have invented certain new and useful Improvements in Work-Guiding Devices for Sewing-Machines, of which the following is a specification, reference being had therein to the accompanying drawings.

10 This invention relates to tuck-forming and stitching devices, and particularly to means for producing simultaneously a plurality of tucks stitched in permanent relations, such as is disclosed in the United

15 States patent to C. H. Foster, No. 575,342, of January 19, 1897; and it has for its object to provide for the release of the work for the shifting or the removal thereof preceding or following a tuck-forming and

20 stitching operation.

In its preferred embodiment, the invention comprises stitch-forming mechanism including a plurality of reciprocating needles arranged in a row crosswise of the 25 direction of feed, a multiple tucking attachment comprising separable upper and lower series of tuck-forming elements disposed respectively in alternating relation, and a presser-foot normally resting upon the work 30 adjacent the stitching point, combined with lifting means including a common element whereby the presser-foot may be raised and the upper tuck-folding element lifted out of operative relation with the lower tuck- 35 folding elements to facilitate the introduction and removal of the work.

Coöperating with the advanced portion of the lower tuck-folding elements is a series of fold-guides having blades which 40 are adjustable both in the direction of and crosswise of their length to insure their proper positioning relatively to the lower tuck-folding elements and the stitch-forming mechanism. The invention also includes 45 tension devices with releasing means therefor operatively connected with said lifting means, whereby the needle-threads may be slackened when the work is released by the presser-foot and tuck-folding elements, to insure unrestricted movement of the work 50 after a stitching period. The invention includes certain other features to be herein-

after described in detail and pointed out in the appended claims.

In the accompanying drawings, Figure 1 55 is a front end elevation of a sewing machine embodying the present improvements, and Fig. 2 a plan of the forward end of the machine with the head of the bracket-arm and certain other parts in section. Fig. 3 is an 60 end elevation of the machine similar to Fig. 1, with certain of the parts in different positions. Fig. 4 is a transverse section on line 4—4 of Fig. 3. Fig. 5 is a perspective view of the upper tuck-folding member and its 65 carrying-arm, and Fig. 6 a similar view of the tuck-guide and its carrier. Fig. 7 is a perspective view upon a larger scale representing the series of tuck-guides with the adjacent portion of the carrier represented 70 in dotted lines. Fig. 8 is a view of the under side of the upper tuck-folding member.

As represented in the drawings, the machine is of the well-known Singer chain-stitch type, and is constructed with a frame 75 comprising the base 1 and bracket-arm 2 terminating in the head 3 in which is journaled the reciprocating needle-bar 4 which is provided at its lower end with the transversely arranged needle-clamp 5 carrying 80 in practice a series of eye-pointed needles 6 arranged in a row disposed at right angles with the line of feed. The needles reciprocate through the usual work-plate 7 beneath which are coöperating loop-takers of suitable or usual form.

Journalized within suitable bearings of the bracket-arm head 3 is the presser-bar 8 having secured upon its lower end the shank 9 of the presser-foot which is normally thrust 90 downwardly by means of the flat spring 10 sustained in a well-known manner upon the bracket-arm and having its free end resting upon the top of the presser-bar. Secured upon the presser-bar by means of the set-screw 11 is a collar 12 embraced within a lateral recess of the sliding sleeve 13 fitted loosely upon the presser-bar and provided near its upper end with the lateral stud-pin 14 and adjacent its lower end with the laterally projecting stud-pin 15 which preferably carries the anti-friction rollers 16 and 17.

The stud-pin 14 enters the apertured for-

ward arm of a rock-lever 18 of well-known form mounted upon the fixed stud-screw 19 sustained by the bracket-arm and having its apertured rearwardly extending arm connected by means of the depending rod 20 with suitable operating means, as a treadle or knee-lever, beneath the sewing machine. Beneath and in operative relation with the roller 16 of the stud 15 is the lifting cam 21 upon the hub of the hand-lever 22 which is mounted upon the fixed fulcrum-stud 23 sustained by the bracket-arm head 3. The operative or eccentrically curved edge of the cam 21 merges at its high point in a concentric portion which terminates with the stop-finger 21' laterally engaging the roller 16 to limit the lifting movement of the lever 22.

Within the depending flange 7' of the work-plate is a vertically apertured boss 24 in which is fitted a depending stud 25 of a plate 26 centrally channeled in its upper face to afford a guideway in which is fitted the depending tongue 27 of a carrier-plate 28 upon which is secured by screws 29 the lower member 30 of the tucking attachment which is formed with the usual convergent forming ribs 31 terminating in the laterally inclined blades 32. The stud 25 is secured 30 in position by means of the set-screw 25' by loosening which the plate 26 may be raised or lowered to afford vertical adjustment for the tuck-forming member 30. The carrier-plate 28 is removably secured in position by means of the fastening screw 27' entering an aperture of the plate 26 and tapped into the tongue 27.

Disposed above the outer portion of the member 30, and with its series of ribs or tuck-folding elements 33 normally in alternating relation with those of the lower member 30, is the upper tuck-forming member 34 which has secured upon its upper face by screw 35 a plate 36 carrying a fastening stud-screw 37 entering and embraced by a slot 38 in a lateral flange 39 at the outer or free end of the arched sustaining lever 40. At its opposite end the lever 40 is formed with an apertured boss 41 entered by the shoulder stud-screw 42 by which such lever is fulcrumed rearwardly of the needle-and presser-bars. Directly above the boss 41, the lever 40 is formed with an upwardly extending cam-finger 43 whose concaved forward edge is adapted to engage the roller 17 of the stud 15.

The stud-screw 42 is tapped into a bracket-piece 44 which is secured to the lower portion of the bracket-arm head 3 by means of 60 screws 45 and is provided with a rearwardly projecting tubular boss 46 having its outer end internally threaded to receive the screw-plug 47. A spring 48 is interposed between the inner end of the plug 47 and a flange 49 65 extending laterally from the cam-finger 43

of the lever 40, and acting through said lever to press the upper folding member downwardly toward the lower folding member. The lever 40 is provided adjacent the boss 41 with an apertured and threaded lug 50 70 within which is fitted the stop-screw 51 whose depending point is adapted to engage the top of the lateral lug 52 extending from the rigidly sustained bracket-piece 44 and affording adjustable means for determining 75 the spacing apart of the upper and lower tuck-forming elements. A lock-nut 53 is applied to the stop-screw 51 to prevent the accidental turning of the latter.

Secured to the forward face of the bracket-piece 44 by the screw 54 and steady-pins 55 is a downwardly and forwardly extending arm 56 having a slotted forward extremity fitted within a channeled transverse seat 57' of a carrier-bar 57 detachably secured thereto 85 by means of a screw 58 passing through the slot of the arm 56 and tapped into said bar. The bar 57 is formed with a series of transverse sockets disposed parallel to the work-plate and to the direction of feed, in which 90 sockets are secured by means of set-screws 59 stud-pins 60 extending from bosses 61 from which depend the laterally and downwardly curved wings 62 which terminate in the tuck-guiding blades 63 in practice overlying those parts of the lower tuck-forming member intermediate the blades 32. By loosening the set-screws 59, the tuck-guiding blades 63 may be adjusted either endwise or sidewise while retaining their substantial 100 parallelism with the portions of the lower tuck-forming member which they overlie.

By mounting the upper tuck-forming member 34 and the tuck-guides 63 upon carriers sustained from a point rearward of the 105 needles, the operator's view of the stitching point remains unobstructed for the easy and accurate manipulation of the work, and the support of the guides 63 by an arm extending horizontally below and to the rear of the 110 eyes of the needles in the upper position of the latter affords an unobstructed space for the convenient threading of the needles. The carrier-lever 40 is preferably arched to a point above the highest position to which 115 the needle-clamp rises so as to afford ample clearance for the needle-clamp of a machine employing a large number of needles and in which the needle-clamp extends laterally beyond the support for the tuck-forming member 34.

The employment of a spring 48 provides for the relative yield of the upper and lower tuck-forming members to accommodate cross-seams and other irregularities in the 125 thickness of the work, and the employment of the screw-plug 47 provides means of adjustment of the tension of this spring so as to produce a pressure upon the work suited to the character of the fabric.

The lifting of the presser-foot may be accomplished by means of the usual treadle or knee-lever acting through the rod 20 to tilt the rock-lever 18, or by the hand-lever 22 5 acting through the cam 21; but in either case, in the present embodiment, the vertical movements of the sleeve 13 effect the desired movements of the presser-foot and the upper tuck-forming member either simultaneously 10 or successively, depending upon the position and adjustment of the mechanism. In the upward movement of the sleeve, the lower member thereof engages the block 12 and carries it with the presser-bar upwardly, 15 and the roller-stud 17 simultaneously moves upwardly and in such movement rides against the cam-shaped edge of the finger 43, thereby rocking the lever 40 upon its fulcrum 42 and lifting the holding member 34, 20 as represented in Fig. 1, these rising movements being performed in opposition to the presser-bar and tuck-former springs 10 and 48, respectively. The release of the sleeve 13 by its lifting means obviously permits the 25 descent of the work-engaging members to operative position under the action of their respective springs.

As shown in the drawings, the present machine is provided with tension mechanism similar to that of my Patent No. 30 1,146,405, of July 13, 1915. The tension devices, which correspond in number to the needle 6, are mounted upon a supporting plate 64 which is carried upon the outer end of the endwise movable rod 65 provided in its opposite end portion with a lateral recess 66 embracing the rounded arm 67 of an elbow-lever mounted upon the fulcrum-stud 68 and having a lateral arm 69 connected by 35 means of the pull-rod 70 with the rearward arm of the presser-foot lifting rock-lever 18. The tension devices are of well-known form, and each comprises the separable disks 71 normally pressed together upon the needle-thread by means of a spring 72 interposed 40 between the outer tension disk and the thrust-nut 73 upon the threaded tubular stem 74.

A tension-release pin 75 entering the bore 50 of the stem 74 and effecting an operative connection with the spring 72 is adapted to engage the stationary thrust-plate 76 carried by the bracket-arm when the supporting plate 64 is drawn backwardly by actuation 55 of the rock-lever 18 so as to relieve the tension disks of the pressure of the springs 72 to slacken the needle-thread when the presser-foot is lifted.

By the provision of common means for 60 lifting the presser-foot and separating the tuck-forming members, the two distinct actions of the operator heretofore required for the purpose in this class of machine become unnecessary, the single lifting action performed by means below the table according

to the present improvement permitting the operator's hands to be entirely free for manipulation of the work. The described advantage in the handling of the work is further increased by the employment of tension-releasing means connected with the lifting means, whereby the stitched and folded fabric is entirely free from the detaining action of the stitching threads when the work is shifted or removed from the machine after a tuck-forming and stitching operation. 70

To permit access to the loopers, the upper tuck-forming member 34 may be removed 80 from its carrier by loosening the fastening screw 37 and withdrawing the same therefrom, the carrying bar 57 for the tuck-guides being similarly detached from its carrying member 56 by loosening the screw 58, after which the removal of the fastening screw 85 27' permits the removal of the plate 28 which closes a suitable access aperture of the bed-plate in a well-known manner.

While the present improvement is shown in the form and arrangement of its component parts which are deemed preferable, it is evident that the improvement may exist in widely different embodiments within the scope of the present invention. Although the present improvement is shown and described herein embodied in a machine for forming and stitching tucks in fabrics, it is evident that the character of the separable work-guiding elements is not an essential 90 part of the invention in its broader aspect. 95

Having thus set forth the nature of the invention, what I claim herein is:—

1. In a sewing machine, in combination a presser-foot, a presser-bar, a tucking guide comprising separable folding elements, a 105 presser-foot lifting lever, and means carried by the presser-bar for lifting the presser-foot and separating the folding elements vertically to facilitate the introduction and removal of fabric. 110

2. In a sewing machine, in combination, a work-plate, a presser-foot movable toward and from the same, lifting means for said presser-foot, a tucking guide comprising co-operating folding elements of which one is 115 movable relatively to the other in the direction of movement of the presser-foot, and means connected with said presser-foot lifting means for lifting the movable folding element for introduction and removal of the 120 fabric.

3. In a sewing machine, in combination, a presser-foot, lifting means therefor, a tucking guide comprising separable folding elements between one of which and the presser-foot a relative yield is provided for, and means connected with said presser-foot lifting means for raising the last-named folding element for introduction and removal of the 125 fabric. 130

4. In a sewing machine, in combination, a presser-foot, lifting means therefor, a tucking guide comprising separable folding elements one of which is mounted to yield relatively to the other and to said presser-foot, and lifting means including a common element for raising the presser-foot and said yieldingly mounted folding element. 50
5. In a sewing machine, in combination, a presser-foot, a spring acting thereon, presser-foot lifting means acting in opposition to said spring, a tucking - guide comprising separable folding elements consisting of intermeshing converging ribs and grooves, a spring for forcing said elements together, and means connected with said presser-foot lifting means for separating said folding elements for introduction and removal of a fabric. 10
6. In a sewing machine, in combination, stitch-forming mechanism, and a tucking guide comprising separable folding elements, a spring for pressing said elements into operative relation, and means for adjusting the tension of said spring. 20
7. In a sewing machine, in combination, stitch-forming mechanism, and a tucking guide comprising upper and lower folding elements, said upper folding element being movable away from said lower folding element in substantially a perpendicular direction, a spring for yieldingly holding said elements in normal operative relation and adjustable means for limiting the action of said spring to vary the normal spacing apart of said elements. 30
8. In a sewing machine, in combination, stitch-forming mechanism including a multiplicity of needles, a needle-bar, a clamp carried thereby for holding said needles, a tuck-guide comprising opposed upper and lower folding elements, said guide being located in advance of the needles, an arched supporting arm extending from said upper member of the guide over and above the needle-clamp when in its extreme upper position, a pivot to the rear of the needles for supporting said arm for movement in a vertical plane parallel with the line of feed whereby unrestricted extension of the needle-clamp is provided for securing a gang of needles equally on both sides of the needle-bar. 40
9. In a sewing machine, in combination, stitch-forming mechanism including a multiplicity of needles, a needle-bar, a clamp carried thereby for holding said needles, a tuck-guide comprising opposed upper and lower folding elements, said guide being located in advance of the needles, an arched supporting arm extending from said upper member of the guide over and above the needle-clamp when in its extreme upper position, a pivot to the rear of the needles at 50 a point below the crest of the arched sup-
- porting arm for supporting said arm for movement in a vertical plane parallel with the line of feed whereby in the movement of the arm about its pivot the horizontal component of motion is substantially eliminated. 70
10. In a sewing machine, in combination, stitch-forming mechanism, and a multiple tucking guide comprising upper and lower series of tuck-forming elements disposed respectively in alternating relation, a series of 75 fold-guides disposed in advance of the upper tuck-forming elements and in operative relation with the lower tuck-forming elements and each constructed with a fold-engaging blade provided with a stud-pin disposed parallel with said blade, a carrier for said fold-guides having a series of parallel sockets disposed parallel with the work-plate, and means for adjustably securing within said pockets said stud-pins of the 80 fold - guides whereby the fold-engaging blades of the latter are adapted for endwise and sidewise adjustment. 85
11. In a sewing machine, in combination, a presser-bar, a presser-foot carried thereby, lifting means applied to the presser-bar and including a stud movable with the latter in performing its lifting movements, a tucking guide comprising separable folding elements, and a carrier for one of said elements 90 movably mounted independently of the presser-bar and adapted to be directly engaged by said stud to lift said folding element. 95
12. In a sewing machine, in combination, 100 a presser-bar having a shoulder, a presser-foot carried thereby, a sleeve surrounding said presser-bar arranged for operative engagement with said shoulder and carrying a plurality of studs, a lifting lever engaging one of said studs, a tucking guide comprising 105 separable folding elements, and a carrier for one of said elements movably mounted independently of the presser-bar and normally lying in the path of movement of another of the studs of said sleeve. 110
13. In a sewing machine, in combination, a presser-bar having a shoulder, a presser-foot carried thereby, a sleeve surrounding said presser-bar arranged for operative engagement with said shoulder and carrying a plurality of studs, a lifting lever engaging one of said studs, a tucking guide comprising 115 separable folding elements, and a carrier-lever for one of said elements ful-crumed independently of the presser-bar and formed with a cam-finger adapted for engagement with another of the studs of said sleeve for effecting the rise of the folding element under the action of said sleeve 120 in lifting the presser-bar. 125
14. In a sewing machine, in combination, stitch-forming mechanism including a plu- 130 rality of reciprocating eye-pointed needles, and a multiple tucking guide comprising

upper and lower series of tuck-forming elements disposed respectively in alternating relation, a series of fold-guides disposed in advance of the upper tuck-forming elements 5 and in operative relation with the lower tuck-forming elements and each constructed with a fold-engaging blade, and a carrier for said fold-guides sustained at a point

rearward of the needles and extending forwardly past the needles adjacent which it lies wholly below the needle-eyes when in extreme upper position whereby the needle eyes are rendered accessible for threading.

In testimony whereof I have signed my name to this specification.

ALBERT H. DE VOE.
